Primary Examiner — Holly E Thurman

(57) **CLAIM**

The ornamental design for a parasol, as shown and described.

DESCRIPTION

1. Reflector for photography or cinematography
The patent or application file contains at least one drawing executed in color. Copies of this patent or patent application publication with color drawing(s) will be provided by the Office upon request and payment of the necessary fee.

1.1 is a front view of the reflector for photography or cinematography showing my new design;

1.2 is a top perspective view thereof;

1.3 is a rear view thereof;

1.4 is an enlarged rear perspective view thereof;

1.5 is another enlarged perspective view thereof;

1.6 is another enlarged perspective view thereof; and

1.7 is another enlarged perspective view thereof.

1 Claim, 7 Drawing Sheets
(7 of 7 Drawing Sheet(s) Filed in Color)
